UNITED STATES PATENT OFFICE.

GEORGE S. MYERS, OF PHILADELPHIA, PENNSYLVANIA.

RAILWAY-TIE.

1,074,062.

Specification of Letters Patent. Patented Sept. 23, 1913.

Application filed January 30, 1913. Serial No. 745,270.

To all whom it may concern:

Be it known that I, George S. Myers, a citizen of the United States, residing at Philadelphia, in the county of Philadelphia and State of Pennsylvania, have invented now and useful Improvements in Railway-Ties, of which the following is a specification.

My invention relates to new and useful improvements in railway ties, and has for its object to provide a device of this character which may be produced from suitable metal such as steel, simple in construction, relatively inexpensive in the cost of manufacture, although strong and durable.

Another object of the invention is to so combine the parts which are used in making the tie, that the rails may have certain movements with relation thereto, overcoming the rigidity generally found in this class of ties.

A still further object of the invention is to provide means for readily and quickly fastening the rails to the ties.

Another object of the invention is to provide means for preventing the rail fastening means from becoming detached, which means will also act as a tie holding device to prevent the tie from slipping either longitudinally or transversely.

With these ends in view this invention consists in the details of construction and combination of elements hereinafter set forth and then specifically designated by the claim.

In order that those skilled in the art to which this invention appertains may understand how to make and use the same, I will describe its construction in details referring by numeral to the accompanying drawing forming a part of this specification, in which—

Figure 1, is an edge view of a tie made in accordance with my improvement showing a pair of rails attached thereto. Fig. 2, a plan view of two adjacent ties, one of them having the nut and bolt removed from one end, and Fig. 3, is an enlarged longitudinal section view through one end of the tie.

In carrying out my invention as here embodied, 2 represents the body of the tie which may be made in any desired length and shape preferably rectangularly and if found desirable, the central portion thereof may be reduced thinner as at 3, than the end portions 4, thus saving considerable

metal, producing a much cheaper tie and making it light in weight so that it may be readily handled.

Adjacent each end of the tie, the body is under cut as at 5, forming a projection 6, having a beveled under face 7, which corresponds to the shape of the upper face of the rail base and from this under cut portion extends an opening 8 for the reception of the holding plate 9, having a projection 10 whose under face is beveled to correspond with the shape of the upper face of the rail base as at 11. In the holding plate is formed an open ended slot 12, and when said plate is mounted upon the tie, said slot alines with a portion of the elongated opening 13 formed in the body 2 of the tie.

The rails 14 are mounted upon the tie with one side of their base lying beneath the projections 6, after which the holding plate 9, is placed in the opening 8 with its projection 10 over-lying the opposite side of the rail base. A bolt 15 preferably passes upward through the elongated opening 13 and into the slot 12 having a nut 16 threaded thereon and engaging the holding plate for fastening said holding plate in position.

When the nut 16 is loosened, the bolt is permitted to slide in the elongated opening 13 and when moved to the innermost end of said elongated opening, the holding plate may be readily removed. After the holding plate has been placed in position, the bolt is moved toward the end of the tie causing it to enter the open ended slot 12 and by threading the nut upon said bolt, the holding plate will be fastened to the tie. In order to prevent said bolt from accidentally moving inward which will allow the holding plate to become loosened, I provide a spike 17 which passes through the elongated opening 13 and is of sufficient thickness to also enter a portion of the open ended slot 12 when the spike 17 is in place, it enters the ground beneath the tie and prevents any movement of said tie.

18 denotes a fish plate, one of which is placed on each side of the rails at a joint being held in place by suitable bolts 19 passing through the fish plate and the web of the rails and having threaded thereon the nuts 20. When the fish plates are in position, their upper edges rest against the under surfaces of the rail head, while their lower edges rest upon the projections 6 and 10.

Of course, I do not wish to be limited to the exact details of construction as here shown as these may be varied within the limits of the appended claims without departing from the spirit of my invention.

Having thus fully described my invention, what I claim as new and useful is—

A tie consisting of a body having a reduced central portion, the body of said tie being under-cut adjacent each end to form inwardly extending projections, the under faces of which are beveled, said body also having an opening leading from the under-cut portion, the body also having elongated openings formed therein, holding plates, each having an open ended slot, mounted in said openings, an integral projection formed with each of said holding plates, the

under faces of which are beveled, a bolt passing through each of said elongated openings and open ended slots, a nut threaded on each of said bolts and engaging the holding plates for detachably fastening the latter in place, and spikes adapted to pass through the elongated openings and lie in a portion of the open ended slots for preventing the accidental displacement of the bolts, said spikes adapted to enter the ground and prevent movement of the tie.

In testimony whereof, I have hereunto affixed my signature in the presence of two subscribing witnesses.

GEORGE S. MYERS.
